His Attorney.

UNITED STATES PATENT OFFICE.

HARRY W. VICKERY, OF LYNN, MASSACHUSETTS, ASSIGNOR TO GENERAL ELECTRIC COMPANY, A CORPORATION OF NEW YORK.

AUTOMATIC SWITCH.

Application filed November 28, 1924. Serial No. 752,529.

My invention relates to electric switches and in particular to an automatic two-way fluid contact switch. In certain localities where electric lights are used, it is prescribed by law that theatre exits shall be provided with emergency lighting facilities in order that a proper illumination of the exits shall be maintained in the event that the regular source of electric supply fails.

10 An auxiliary source of electric supply such as a storage battery may be provided to which the lights may be connected whenever the regular source fails. As soon as the regular source is again established, the lights

15 should be promptly switched back to the regular system in order to preserve the storage battery. It is required that the switching operation be controlled automatically in response to a failure in the regular

20 source of supply.

My invention relates to a simple, rugged, reliable switch, particularly designed for performing the functions above mentioned although the switch is by no means limited

25 to such use.

In carrying my invention into effect, I prefer to provide a pair of enclosed chambers containing a suitable gas and connected together by a capillary connection in which is entrapped a quantity of conducting fluid such as mercury forming a circuit terminal. Each chamber contains another circuit terminal arranged to alternately connect with the terminal formed by the conducting liquid in the communicating tube. An electric heater is provided for one chamber and is permanently connected across the regular source of supply so that when this heater is energized, the fluid in the capillary tube will be forced toward the other chamber to connect with the terminal therein. When the regular source of supply fails, the gas in the heater chamber quickly contracts and the readjustment of the gas pressure forces the conducting liquid to break connection in the other chamber and make connection in the chamber provided with the heater.

The features of my invention which are believed to be novel and patentable will be pointed out in the claims appended hereto. For a better understanding of my invention, reference is made in the following description to the accompanying drawing in which Fig. 1 shows a preferred embodiment of my invention and its circuit connections as used

for an emergency lighting installation; and Fig. 2 represents a different operating condition of the switch shown in Fig. 1.

Referring now to Fig. 1, 10 and 11 represents two parts of a sealed container made 60 of some such material as glass. 10 may be called the heating chamber and 11 the expansion chamber. These chambers are connected together at their lower ends by the U-shaped tube 12 and each chamber contains 65 cup portions 13 and 14 at their lower extremities separated from the U-shaped communicating tube 12 by low dams 15 and 16 formed in the bottom walls of the chambers. The cups and the U tube contain sufficient 70 conducting fluid 17 such as mercury to overflow one or the other of the dams, the condition of the fluid depending upon the relative gas pressures in the two chambers. The cups and the lower extremities of the U tube 75 contain electric terminals 18, 19 and 20 sealed in the glass walls to connect the conducting fluid to external circuits. The heating chamber 10 contains an electric heater 21 above the level of the fluid which is connected by sealed-in terminals 22 to the exterior of the chamber.

In the installation represented, the heater filament is connected to a regular source of supply represented at 23 and when voltage 85 exists on this circuit, the heater is energized and heats the gas contained in chamber 10, thereby forcing the conducting fluid to the condition represented in Fig. 1 with dam 15 uncovered and dam 16 covered. The terminal 20 of the expansion chamber is connected to one side of source 23 by a connection 24. The other side of source 23 is connected to one side of a load 25, represented as lights, by a connection 26. The terminal 19 of the central U tube is connected to the other side of the load 25. It will thus be seen that so long as voltage exists across source 23, this source will be connected to the load 25 by reason of the fluid contact circuit between terminals 19 and 20 above the dam 16. A second source of supply 27, represented as a storage battery, is connected between the line 26 to the load and the terminal 18 of the heating chamber. Now, 105 should the source 23 fail, filament 21 will be deenergized and the gas in chamber 10 will quickly cool allowing the fluid conductor to readjust its condition to that represented in Fig. 2 where it will be noted that 110

the dam 16 is uncovered and dam 15 is covered. This disconnects the load 25 from source 23 and connects it to the storage battery 27 through terminals 18 and 19 and the fluid conductor between them. As soon as the voltage again comes on source 23, the filament 21 will be energized and the connections represented in Fig. 1 reestablished. The amount of fluid conductor in the chambers 10 and 11 is preferably such that the circuit is broken at one dam just before it is made at the other. The dams may be of sufficient width to break a considerable current amperage without destructive heating of the glass. As represented in the drawings, the dam 16 in the expansion chamber has a slightly higher level than that of the heating chamber. With such an arrangement the gases in the two chambers should be of such volume as to make the fluid level about equal when the heater 21 is deenergized as represented in Fig. 2, leaving the higher dam uncovered and the lower dam covered. It is not essential, however, that the dams have the relative heights represented, since other relations can readily be compensated for by a readjustment of the gas pressure in the two chambers. For the best economy the two dams should be nearly the same level. The relative gas pressures in the two chambers may readily be altered by tipping the device one way or the other and then allowing the mercury to flow back in the tube 12 and the relative levels of the two dams can be altered by a slight tipping of the device in the proper direction. The heater 21 is preferably placed inside of the vessel 10 and is of such resistance as to take a very small current and to be quickly heated to incandescence and thus operates as a visible signal to indicate the condition of the switch. The two chambers, being equally exposed to the surrounding air, are equally affected by changes in ambient temperature and the operation of the switch is therefore independent of such temperature changes. Such an automatic switch is quiet, economical and reliable in its operation and is quickly responsive to the failure and the reestablishment of the voltage on source 23. It is simple and rugged in construction, requires no attention and is equally suitable for direct or alternating currents on either source. It has no exposed contacts or coils and consequently is highly desirable from the standpoint of fire safety.

In accordance with the provisions of the patent statutes, I have described the prin-

ciple of operation of my invention, together with the apparatus which I now consider to represent the best embodiment thereof, but I desire to have it understood that the apparatus shown and described is only illustrative and that the invention may be carried out by other arrangements.

What I claim as new and desire to secure by Letters Patent of the United States is:

1. A two-way switch comprising a heating chamber and an expansion chamber containing a heat expansible gas, said chambers being connected together by a tube in which there is entrapped a quantity of conducting fluid, fluid contacts in each chamber separated from the tube by low dams and an electric heater in one chamber adapted to cause the fluid in said tube to alternately overflow said dams when said heater is energized and deenergized respectively due to the variation in gas pressure under said conditions.

2. A two-way switch comprising a pair of sealed containers connected together by a U-shaped tube, depressions in said containers separated from said tube by low dams, a quantity of conducting fluid in said depressions and tube just sufficient to cause the fluid to overflow one dam only, a heat expansible gas contained in said chambers and separated by the conducting fluid in said tube, an electric heater contained in one of said chambers for operating the switch, said heater being adapted to be heated to incandescence when energized and thereby serve as an indication of the condition of the switch.

3. In a switching device, a sealed container comprising a heating chamber and a compression chamber, a U-shaped tube connecting said chambers, a depression in the compression chamber separated from the tube entrance therein by a low dam, conducting fluid in said tube and depression, external circuit terminals sealed into said container to connect the fluid in said tube and depression to external circuits, an electric heater in the heating chamber and a heat expansible gas in said chambers, the relative pressures in the two chambers being such as to cause the fluid to overflow said dam when the heater is energized and to uncover said dam when the heater is deenergized.

In witness whereof, I have hereunto set my hand this 25th day of November, 1924.

HARRY W. VICKERY.
